UNITED STATES PATENT OFFICE.

EDWIN E. SLICK, OF WESTMONT BOROUGH, PENNSYLVANIA.

METALLIC TIE.

1,125,888.

Specification of Letters Patent. Patented Jan. 19, 1915.

Application filed June 12, 1912. Serial No. 844,802.

To all whom it may concern:

Be it known that I, EDWIN E. SLICK, a citizen of the United States, residing in the borough of Westmont, in the county of Cambria and State of Pennsylvania, (whose post-office address is Johnstown, Pennsylvania,) have invented certain new and useful Improvements in Metallic Ties; and I do hereby declare the following to be a full, clear, and exact description of the invention, such as will enable others skilled in the art to which it appertains to make and use the same.

My invention is particularly adapted for improvements in railway ties and fastening devices therefor, one of the particular objects being the means whereby the rails may be easily secured to the ties and readily removed therefrom when desired.

A further object of my invention is the manner of constructing the joints of the track so that it may be quickly put together or taken apart, no fish-plates nor splice bars being needed.

Another object of my invention is to secure the rail fastening devices permanently to the ties to prevent the loss of the same. The rail securing devices are button fastenings which may be turned to engage or disengage the base flanges of the rail, as desired.

My invention is particularly adapted for use in mines, factories, on farms, plantations, in construction work or the like, and it is particularly well adapted for use in cases where it is necessary to move portions of the track as the work progresses.

My invention further consists in the novel construction, combination and arrangement of parts hereinafter more particularly described.

Having thus given a general description of my invention, I will now, in order to make the same more clear, refer to the accompanying one sheet of drawings forming a part of this specification and wherein like numerals of reference indicate like parts throughout the several views.

Figure 1 is a top plan view of my improved tie showing one form of my fastening device for securing the rails on the ties, comprising buttons each having projections at each end for contacting with the rail base flanges. Fig. 2 is a side elevation of the tie and rail fastening devices shown in Fig. 1, the rails being shown in transverse

section. Fig. 3 is a top plan view showing another form of rail fastening device wherein the buttons have only one lug projection for contacting with the base flanges of the rails and illustrating the manner of attaching the abutting ends of the rails to the ties. Fig. 4 is a transverse sectional view on an enlarged scale of the tie taken on the line IV—IV of Fig. 3, the abutting ends of the rails and the fastening devices being shown in elevation, and in this figure, the righthand fastening is in its locked position and the lefthand fastening device is in its unlocked position.

Referring now to the various characters of reference on the drawings:—1 indicates the tie, which may be pressed or rolled into shape, having a central longitudinal groove 2, downwardly extending flanged side edges 3 and intermediate flat rail seat portions 4. Suitably spaced holes 5 are punched or drilled through the flat portions 4 of the ties near each end, preferably four being punched near each end of those ties which are used at the rail joints, as shown in Figs. 3 and 4, while two at each end of the tie will be sufficient for the intermediate ties between the joints, as illustrated in Figs. 1 and 2. The shank of the fastening means 6 which passes through the tie is cylindrical, so as to facilitate the turning of the fastening or button, as desired.

The clamping buttons are indicated at 6 in Figs. 3 and 4 with an enlarged head portion 7 formed with a projection 8 for contacting with the tops of the rail base flanges, and a rounded side edge 9 is formed on the head 7 under the projection 8 to hold the rail against lateral displacement, while allowing the button to be turned when desired. The head of the button 6 is formed with a cylindrical stud projection 10 which is inserted through holes 5 and the ends are clenched or expanded by means of a riveting tool as at 11 on the under side of the tie to form a pivoted connection between the tie and the button. In some cases I may place a washer 12 on the stud 10 of the button before clenching it as shown on the righthand fastening device of Fig. 4.

In Figs. 1 and 2 I have shown the heads of the buttons with a central, preferably cylindrical, portion 13 which contacts with the side edges of the base flange of the rail, and oppositely extending projections 14 above the cylindrical portion 13 for engag-

ing the top outer edges of the base flanges of the rail, otherwise the clenching of the buttons on the ties may be the same as hereinbefore described.

5 Before placing a rail on the tie the inner buttons with the head projections 8 or 14, depending upon which kind of button is used, are turned transversely of the tie as illustrated in the lefthand side of Fig. 4 of the drawings. After the rail is placed in position the buttons are turned by means of a suitable wrench, so that the projections 8 or 14 overlap on the edges of the base flanges of the clamps, while the lower cylindrical portions of the button above the tie preferably contact with the ends of the base flanges of the rails, so as to hold the track to proper gage. It should be noted that the buttons illustrated in Figs. 1 and 2 are 10 double ended buttons, in that they have projections at each end, so that in case one of these projections should become inoperative or worn, the other can be used. The buttons illustrated in Figs. 3 and 4, however, 15 are somewhat different, and each of these has only one projection 8, the other and opposite ends of the buttons being provided with an oppositely extending projection, the lower surface of which is adapted to contact 20 with the upper surface of the tie and act as a lever in firmly holding the button in position to withstand the pressures which might be applied to it in use.

One of the particular features of my arrangement is that the buttons are riveted in place on the tie, the final pressure between the contacting surface of the rivet and the tie being such that the friction caused by such pressure is considerably less than the 25 torsional strength of the shank portion of the rivet which passes through the hole in the tie. I therefore provide a button fastening which is held in position by frictional contact, but which at the same time may be 30 moved to open or close the fastening whenever desired without twisting off the shank. If necessary, I prefer to make the hole 5 in the tie with smooth edges and also to make 35 the top and bottom of the tie smooth where the buttons contact with it. This allows me 40 to arrange the button with friction sufficient to hold it in any position desired, while at the same time it is readily turned without fear 45 of twisting it.

50 As shown at the righthand side of Fig. 4, I provide a washer which may be flat, or which, previous to being riveted in place may be slightly bent or concaved. This produces a certain form of spring action which 55 gives turning friction to the fastening while at the same time it prevents the friction being so great as to twist off the shank of the rivets. In order to provide a fastening, the 60 friction of which would be sufficient to hold 65 it, but at the same time allow it to be read-

ily turned without danger of twisting it off, I may heat the rivet to a somewhat lesser degree than customary in ordinary riveting, or in fact, I may drive the heads cold by suitably arranging the riveting pressures, 70 with due regard to the contractile forces which will be set up in the riveting, due to cooling, and so adjust the friction so that the button fastening acts in the manner indicated. The smoothness of the adjacent 75 parts also aids in proper operation and maintenance of my fastening device.

One of the particular advantages of my tie resides in the fact of its lightness and strength and stiffness, the stiffness being 80 augmented by the downwardly projecting flanges on the edges and by the longitudinal groove or depression formed intermediate of the flanges.

For use in mines, I prefer to make the 85 depth of the tie only about one-half inch, which gives a great advantage in small coal seams or openings, as, on account of the slight depth of the tie, much greater clearance is provided between the top of the rail 90 and the roof of the mine, which allows the use of larger mining machines, allows the miner to more readily load the coal over the sides of the car and obviates any necessity of cutting channels or grooves in the floor 95 of the mine to receive the tie, as is customary where wooden ties three or four inches thick are used.

Although I have shown and described my improvements in considerable detail, I do 100 not wish to be limited to the exact and specific details shown and described, but may use such substitutions, modifications or equivalents thereof, as are embraced within the scope of my invention, or as pointed out 105 in the claims.

Having thus described my invention, what I claim and desire to secure by Letters Patent is:—

1. The combination with a metallic tie of 110 revoluble rail fastening buttons riveted therein and frictionally held in predetermined position.

2. A metallic tie of inverted shallow trough-section, revoluble rail fastening buttons riveted therein adapted to project over the rail flanges, and held in predetermined position by friction.

3. The combination with a metallic tie of 115 circular holes of smooth contour and surroundings, rail fastening buttons riveted therein, said buttons being provided with projections adapted to project over the rail flanges, to revolve on their axes and maintained in predetermined positions by friction.

4. The combination with a metallic tie 120 provided with cylindrical holes near the rail seat portions, of rail fastening buttons provided with cylindrical shanks mounted in 125

- said holes, said buttons having projections adapted to overlap the rail flanges and abutment projections opposite said first named projections adapted to bear against the upper surface of the tie, said buttons being revoluble, capable of being set in positions and there maintained by frictional contact with the tie.
5. The combination with a metallic tie 10 provided with cylindrical openings near its seat portions, of rail fastening buttons fitting and riveted in said holes, each button having a projection adapted to overlap the edge of the rail flange and a rounded portion of diameter greater than the shank 15 adapted to abut the edge of the rail flange, the buttons being so riveted as to be capable of being turned around the axes of their shank portions and held in predetermined position by frictional contact with the tie. 20
6. The combination with a metallic tie of revoluble rail fastening buttons riveted therein, rails having their ends abutting on the said tie, said buttons being frictionally held in predetermined positions and adapted 25 to contact with the rail flanges and thereby secure the rails to the tie.

In testimony whereof I hereto affix my signature in the presence of two witnesses.

EDWIN E. SLICK.
